STABILIZING DEVICE

Marcel Louis Gianoli, Neuilly-sur-Seine, France

Application November 24, 1937, Serial No. 176,306
In France November 30, 1936

5 Claims. (Cl. 244—82)

The present invention relates to automatic stabilizing devices for aerial or marine movable objects, composed of a main surface pivoted on the body of the movable object, of an auxiliary surface pivoted on the main surface, and of a kinematic connection between the auxiliary surface and the body of the movable object compelling said auxiliary surface to modify its position relatively to the main surface when the latter itself modifies its position relatively to the body of the movable object.

It is advantageous for stabilizing devices of this kind which operate according to the modifications in direction of the wind or relative stream, to be placed at the rear of the movable object; this arrangement, in fact, automatically ensures the damping of the oscillations of the movable object. But it is then necessary that the stabilizing device should be devised in such a manner that a change of direction (or rotation) of the relative wind causes the main surface to rotate in reverse direction to said rotation of the relative wind, for increasing the reaction produced by the relative wind on said surface. Now, up to the present moment, in stabilizing devices which satisfy this condition, the auxiliary surface is placed in front of the main surface, which, for that purpose, is provided with arms supporting at the front the pivot of the auxiliary surface. The invention is adapted to provide a stabilizing device of the same kind, but more simple, lighter and stronger, in which the auxiliary surface is pivoted at the rear of the main surface.

Stabilizing devices indeed exist in which the auxiliary surface is pivoted at the rear of the main surface; but these known devices, under the effect of a rotation of the relative wind, rotate in the same direction as said rotation of the relative wind instead of rotating in reverse direction, as in the devices to which the invention relates.

The invention is characterized by the fact that the pivot of the main surface is located behind its center of thrust and the pivot of the auxiliary surface behind the main surface, whilst the kinematic connection between the body of the movable object and said auxiliary surface compels the latter, when the main surface rotates in a certain direction, relatively to the body of the movable object, to rotate in the same direction relatively to the main surface.

Arrangements of the same kind are already known in non-automatical controlled rudders, but in these controlled rudders the main surface is

not entirely loose on its pivot, since it is connected by a rod system or the like to a control member mounted on the body of the movable member and actuated by the pilot. The invention, on the contrary, is applicable exclusively to the case in which the main surface is entirely loose on its pivot and has no connection with the movable member.

In the accompanying drawings:

Fig. 1 is a diagrammatic view of the pivotally mounted main surface, the surface being shown in two positions corresponding to two directions of the relative wind acting thereon.

Fig. 2 is a graphical representation of the torque exerted by the relative wind acting on the main surface and when in the directions indicated in Fig. 1.

Fig. 3 is a diagrammatic view of the auxiliary surface which is pivoted to the main surface, the auxiliary surface being shown in two positions corresponding to the positions of the main surface shown in Fig. 1.

Fig. 4 is a graphical representation of the torque exerted by the relative wind acting on the auxiliary surface and when in the directions indicated in Fig. 3.

Fig. 5 is a diagrammatic view of an automatic stabilizing device in accordance with the present invention.

Fig. 6 is a graphical representation of the torque exerted by the relative wind acting on the surfaces of said device.

Fig. 7 is a view in elevation of a steering rudder for an aeroplane constructed in accordance with the present invention.

Fig. 8 is a sectional elevation on the line 8—8 of Fig. 7, and

Fig. 9 is a sectional plan on the line 9—9 of Fig. 7.

Element A.—(Fig. 1.) This element is composed of a plane 1, pivoted at 2 on a fixed support, the pivot pin 2 being located in front of the center of thrust. Said element is shown in full lines for the position of unstable equilibrium it occupies when the relative wind is directed according to the arrow f.

In Fig. 2 is shown in full lines the curve 3 representing the torques exerted by the relative wind having a direction f, on the plane 1 when this plane is caused, by any means whatever, to form any angle with the direction f.

In the working zone contemplated, the torques are proportional to the angles, and they are evidently of the same signs, since these torques tend to still further space the plane 1 from the di-

rection β ; the assembly is therefore unstable. The angles are shown in abscissae, the torques in ordinates, and the angular coefficient of the straight line 3 is positive.

5 The plane 1 being loosely pivoted at 2 , if the relative wind takes the direction β' , forming an angle β with the direction β , it would be necessary to cause the plane to rotate up to the position shown in dotted lines in Fig. 1, which forms an angle β with the direction β in order that this plane should again take a position of unstable equilibrium. At this moment, the curve 3 comes to 4 , as shown by the dotted lines of Fig. 2, which amounts to saying that, when the direction of the relative wind varies to the extent of $\pm\beta$, the position of unstable equilibrium of the plane 1 is offset also to the extent of $\pm\beta$.

Element B.—(Fig. 3.) This element is a plane 5 , which is pivoted at 6 on an arm 7 , pivoted at 8 on a fixed support. The arm 7 is set in the same direction as the relative wind having a direction β . The plane 5 is, on the other hand, connected to the fixed support in such a manner that to any movement of the arm 7 relatively to said support, corresponds a movement of the plane 5 relatively to the arm 7 . This movement must be such that the angle β passed over by the plane 5 relatively to the arm 7 is equal to na , n being a coefficient higher than -0 , that is to say positive.

30 In these conditions, the device is obviously stable, since to any movement of rotation of the arm 7 relatively to the support, the direction of the relative wind remaining fixed, corresponds a torque tending to restore the whole to the initial position. If the wind turns to the extent of the angle β , the device retakes a position of equilibrium after such a rotation (see dotted lines of Fig. 5) that:

$$40 \quad a + na = i$$

$$a(1+n) = i, \text{ and } a = i \frac{1}{1+n} = ki$$

with the relation:

$$45 \quad \alpha < k$$

In these conditions, the curve for $i=0$ is illustrated at 9 in Fig. 4, and the curve for a certain value of i is illustrated at 10 , this curve being offset to the extent of ki .

50 These elements A and B are known; the invention results from the combination of these elements, which combination is so established that the following conditions are obtained which characterize the autopter:

55 (a) The device presents a curve characteristic of a stable equilibrium;

(b) After the rotation >0 of the relative direction of the fluid stream, the null ordinate point of said stability curve has a negative abscissa which amounts to saying that for reaching its new position of equilibrium, the device has rotated in reverse direction to the rotation of the fluid stream.

65 The equation of the stability curves of the element A, which is a straight line, as explained, is of the form

$$y = ax + b$$

The null ordinate point has for abscissa

$$70 \quad x_0 = -\frac{b}{a}$$

As

$$x_0 \text{ is } > 0$$

75 (see Fig. 2) b and a are of reverse signs. The

same is true for the element B the curve of which is of the form

$$y' = a'x + b'$$

The resulting curve has therefore for equation:

$$Y = (a+a')x + (b+b')$$

and the null ordinate point has for abscissa:

$$x_0 = -\frac{(b+b')}{a+a'}$$

10 In order that the apparatus thus obtained should have the characteristic property a , it is first necessary that $(a+a')$ should be negative, then, in order that it should have the characteristic b , that one should have

$$15 \quad x_0 = -\frac{(b+b')}{a+a'} < 0 \text{ that is to say } b+b' < 0$$

The condition

$$20 \quad b+b' < 0 \text{ gives:}$$

$$-ai - a'ki < 0$$

$$-a'ki < ai$$

$$25 \quad k < \frac{a}{-a'}$$

$$\frac{1}{1+n} < \frac{a}{-a'}$$

$$-a' < a + na$$

$$30 \quad \frac{-a' - a}{a} < n$$

or again

$$35 \quad n > \frac{a' + a}{-a}$$

If this condition is satisfied, the device forming the subject-matter of the invention is obtained, illustrated in Fig. 5 and the curve of which is shown in Fig. 6.

40 By way of example only, a practical embodiment of the system according to the invention will be described hereinafter in reference to Figs. 7, 8 and 9.

45 The main rudder 1 is loosely pivoted, at its front third portion at the rear of its center of thrust, on a supporting tube or rudder-post 81 rigid with the fuselage 82 . This plane 1 is constituted by a structure having a leading edge 83 connected by ribs 84 to a longeron 85 supporting the pivotal joints of an auxiliary surface 5 . The main plane 1 is pivoted on the supporting tube 81 through the medium of the ball bearing 86 and the smooth bearing 87 . The supporting tube is held in position at its upper part by the fitting 88 secured to the cables 89 connected to the fixed part of the horizontal empennage, and, at its lower part, by the fitting 90 secured by bolts to the fuselage structure.

50 The adjustable ball and socket member 81 is connected by a rod or link 82 to the ball and socket joint 83 carried by the lever 84 secured by bolts to the auxiliary surface 5 . The adjustment of the ball and socket member 81 is obtained by the rotation of the aileron lever 85 carrying the same and which is rigid with the double aileron lever 86 . The latter is controlled by cables 87 secured at 88 and 89 to this aileron lever and which lead to the pilot's cock-pit. Fairings 100 and 101 terminate the plane.

55 What I claim as my invention and desire to secure by Letters Patent is:

60 1. In a stabilizer for aerial vehicles, a first pivot secured on the vehicle, a first material sur-

- 5 face freely mounted on said first pivot, and free of any other connection with the vehicle and having the center of thrust in front of said first pivot in order that any change in direction of the relative wind should produce on said surface a stress which tends to cause it to rotate for increasing the angle formed by said surface with the new direction of the wind, a second pivot secured on the rear part of said first material surface, a second material surface mounted on said second pivot and means for connecting said second material surface to said vehicle in order that the rotation of said first material surface should produce a relative rotation in the same direction of the second material surface which then creates, under the action of the relative wind, a stress exerted on said first material surface for limiting the angle of rotation of said first surface.

10 2. In a stabilizer for aerial vehicles, a first pivot secured on the vehicle, a first material surface freely mounted on said first pivot, and free of any other connection with the vehicle and having the center of thrust in front of said first pivot in order that any change in direction of the relative wind should produce on said surface a stress tending to cause it to rotate for increasing the angle formed by said surface with the new direction of the wind, an arm rigid with said first material surface and directed behind the latter, a second pivot mounted at the rear of said arm, a second material surface mounted on said second pivot and means for connecting said second material surface to said vehicle in order that the rotation of said first material surface should produce a relative rotation in the same direction of the second material surface which then creates, under the action of the relative wind, a stress exerted on said first material surface and for limiting the angle of rotation of said first surface.

15 3. In a stabilizer for aerial vehicles, a first pivot secured on the rear part of the vehicle, a first material surface freely mounted on said first pivot, and free of any other connection with the vehicle and having the center of thrust in front of said first pivot in order that any change in direction of the relative wind should produce on said surface a stress which tends to cause it to rotate for increasing the angle formed by said surface with the new direction of the wind, a second pivot mounted at the rear of said first material surface, a second material surface mounted on said second pivot and means for connecting said second material surface to said vehicle in order that the rotation of said first material surface should produce a relative rotation in the same direction of the second material surface which then creates, under the action of the relative wind, a stress exerted on said first material surface for limiting the angle of rotation of said first surface.

20 4. In a stabilizer for aerial vehicles, a first pivot secured on the rear part of the vehicle, a first material surface freely mounted on said first pivot, and free of any other connection with the vehicle and having the center of thrust in front of said first pivot in order that any change in direction of the relative wind should produce on said surface a stress which tends to cause it to rotate for increasing the angle formed by said surface with the new direction of the wind, a second pivot mounted at the rear of said first material surface, a second material surface mounted on said second pivot, an arm connected to said second material surface, a link for connecting said arm to a point of said vehicle in order that the rotation of said first material surface should produce a relative rotation in the same direction of the second material surface which then creates, under the action of the relative wind, a stress exerted on said first material surface for limiting the angle of rotation of said first surface.

25 5. In a stabilizer for aerial vehicles, a first pivot secured on the rear part of the vehicle, a first material surface freely mounted on said first pivot, and free of any other connection with the vehicle and having the center of thrust in front of said first pivot in order that any change in direction of the relative wind should produce on said surface a stress which tends to cause it to rotate for increasing the angle formed by said surface with the new direction of the wind, a second pivot mounted at the rear of said first material surface, a second material surface mounted on said second pivot, an arm connected to said second material surface, a link for connecting said arm to a point of said vehicle in order that the rotation of said first material surface should produce a relative rotation in the same direction of the second material surface which then creates, under the action of the relative wind, a stress exerted on said first material surface for limiting the angle of rotation of said first surface, means for modifying the position of the point of the vehicle to which the link is connected.
